FIG. 1 is a perspective view in an opened position of a corrugated tube clamp.

FIG. 2 is a perspective view in a clamped position of a corrugated tube clamp.

FIG. 3 is a perspective view while in use of a corrugated tube clamp.

FIG. 4 is a front elevation view while in use of a corrugated tube clamp.

FIG. 5 is a top plan view while in use of a corrugated tube clamp.

FIG. 6 is a left side elevated view while in use of a corrugated tube clamp.

FIG. 7 is a perspective view while in use (small corrugated tube) of a corrugated tube clamp.

FIG. 8 is a front elevation view while in use (small corrugated tube) of a corrugated tube clamp.

FIG. 9 is a top plan view while in use (small corrugated tube) of a corrugated tube clamp; and,

FIG. 10 is a left side elevation view while in use (small corrugated tube) of a corrugated tube clamp.

The broken lines shown in the drawings represent unclaimed portions of the corrugated tube clamp and form no part of the claimed design.

1 Claim, 5 Drawing Sheets
